UNITED STATES PATENT OFFICE.

EUGENE A. BRADBURY, OF CANON CITY, COLORADO, ASSIGNOR OF ONE-HALF TO GRANT DICKINSON, OF CANON CITY, COLORADO.

SUSPENSION-CRADLE.

SPECIFICATION forming part of Letters Patent No. 761,058, dated May 31, 1904.

Application filed September 15, 1903. Serial No. 173,302. (No model.)

To all whom it may concern:

Be it known that I, EUGENE A. BRADBURY, a citizen of the United States, residing at Canon City, county of Fremont, State of Colorado, 5 have invented certain new and useful Improvements in Suspension-Cradles; and I do hereby declare the following to be a full, clear, and exact description of the invention, such as will enable others skilled in the art to which it

10 appertains to make and use the same.

My invention relates to swinging cradles and the like, and has for its object to provide an elastic suspension between the body and the supporting-standard so applied that the 15 body may be swung in either a longitudinal or a transverse direction with a gentle and easy movement entirely free from shocks or jerks.

To this end the invention comprises a body 20 swung from a supporting-standard by means of spiral springs or equivalent elastic suspension devices, each of which is attached to opposite points on the cradle-body and to a single point or support on the standard, so that 25 said springs extend downwardly and inwardly from said points of support. In order to compensate for any tipping action due to the occupant moving to one side of the central line, additional springs are attached to the ends of 30 the body, the ends of said springs being secured to opposite sides of the body and the middle points having sliding connection with suitable supports on the standard, so that by pulling said springs through the supports additional tension is placed on that portion of 35 each spring which supports the surplus load. Additional springs connected to the lower side of the body and the lower portion of the standard serve to prevent sidewise tipping and add 40 to the regularity and evenness of the swinging motion.

In the accompanying drawings, Figure 1 is a perspective view of my improved cradle. Fig. 2 is an end view thereof.

45 Referring to the drawings, 1 represents the body of the cradle, which may be given any desired form. Said body is suspended in a supporting-standard of any approved type, but which for strength, stability, and cheap-

ness is preferably constructed of iron pipe- 50 sections and pipe-fittings, as illustrated, 22 indicating the end-uprights, which are secured to the bottom horizontals 33 by T-couplings and are connected at the top by longitudinal pipe-section 5. Casters or rollers 4, mounted 55 in the ends of the bottom pieces 3, permit the cradle to be readily moved from place to place.

The distance between the uprights 22 is somewhat greater than the length of the cradle-body 1 to permit the latter to have a limited longitudinal movement as well as a lateral oscillation when it is suspended from the supporting-standard.

The suspension devices consist of coiled 55 springs 66, each of which is attached at its ends to hooks 12 or other suitable connectors located at opposite points on the body 1, preferably at the corners thereof, and the middle portion of said spring is passed through and 70 supported in eye 8 or equivalent hanger on the upper part of upright 2. The spring 6 at the head end of the cradle is preferably stronger than the corresponding spring at the opposite end in order that the head end 75 may be slightly elevated under normal conditions and also to prevent said end from sagging when the child occupies the upper portion of the cradle. It will thus be seen that the suspension-springs extend diagonally 80 downward and outward from the supporting-eye 8 to the points of connection with the body at the sides whereby much freedom of movement of the body is permitted, and yet all of the advantages of a pivotal suspension 85 of the cradle at its ends is maintained. It will also be seen that the suspension-springs extend longitudinally with respect to the body of the cradle from its ends to the uprights and that the tension of the springs combined 90 tends to hold the body normally in a central position between the uprights, but allows it to swing laterally as well as longitudinally.

In order to further steady the oscillations of the body 1 to compensate for any tendency to overbalance and to restore the body to level equilibrium—as, for instance, when the occupant moves to one side or the other

- of the middle—auxiliary suspension-springs 7, attached at their ends to hooks 12, are adjustably supported at their mid-portions upon hooks 9 upon the uprights 2. By moving the point of engagement of spring 7 with hook 9 the tension of the portions of said spring lying on opposite sides of the hook may be nicely adjusted to keep the body level under all conditions.
- 10 Springs 10, each attached by one end to a lower corner of the body 1 and at the other to a collar 11 on the upright 2, serve to further steady the swinging movement of the body and prevent the latter from tipping or 15 turning over.

Having thus described my invention, what I claim is—

1. In a swinging cradle, the combination with the body and a supporting-standard 20 therefor, of suspension-springs between the ends of the body and the standard, each of said springs being attached to opposite points on the sides of the body and to a common point on the standard centrally of the body,

and auxiliary suspension-springs each having 25 a fixed connection at opposite points on the sides of the body, and an adjustable connection with a common point on the standard centrally of the body.

2. In a swinging cradle, the combination 30 with the body and a supporting-standard therefor, comprising a vertical upright at each end, of suspension-springs between the ends of the body and the respective uprights, each of said springs being attached to opposite 35 points on the upper sides of the body, and extending diagonally upward and inward to a common point on its upright centrally of the body, and steadyng-springs extending upward from the lower part of the uprights and 40 attached to the body at opposite points at the lower sides.

In testimony whereof I affix my signature in presence of two witnesses.

EUGENE A. BRADBURY.
